INVENTOR BY
Louis Laurier Leo. Atty's.

UNITED STATES PATENT OFFICE.

LEOPOLD JOSEPH ARTHUR LAURIER, OF ST. PAUL, MINNESOTA.

TOBACCO-MOISTENING APPARATUS.

SPECIFICATION forming part of Letters Patent No. 324,853, dated August 25, 1885.

Application filed May 9, 1885. (No model.)

To all whom it may concern:

Be it known that I, LEOPOLD JOSEPH ARTHUR LAURIER, a citizen of the United States, and a resident of St. Paul, county of Ramsey, 5 and State of Minnesota, have invented certain new and useful Improvements in Tobacco-Moistening Apparatus, of which the following specification is a full, clear, and exact description, reference being also had to the accompanying drawings, in which—

Figure 1 is a cross sectional view, and Fig. 2 is a longitudinal sectional view, of a show-case with my improvement arranged therein. Fig 3 is an enlarged cross-sectional view, and 15 Fig. 4 is an enlarged longitudinal sectional view, of a portion of one end of one of the moisture-retaining cases detached.

This invention consists in a moisture-retaining apparatus constructed substantially 20 as herein set forth and placed in the upper part of a show-case or other receptacle for cigars, &c., whereby the atmosphere within such show-case may be impregnated with moisture, as hereinafter shown.

25 It is found that cigars retain their flavor longer if in a moist condition, which is usually accomplished by confining them in show-cases or other receptacles in which the air is kept charged with moisture; and to 30 impregnate the air in such show-cases and other receptacles more fully with moisture is the object of my invention, which, as before stated, consists in a moisture-retaining apparatus as herein described placed in the 35 upper part of the show-case or other receptacle, it being a well-known principle of natural law that moist air, being heavier than dry air, will descend, while dry air will ascend; hence, if the moisture-producing substance be placed at the top of the show-case, 40 the air, as it comes in contact therewith, will be charged with moisture and descend to the bottom, driving the drier air to where it in turn becomes charged with moisture and falls 45 to the bottom of the show-case, thus keeping up a slight circulation of the air and keeping all the air charged with moisture.

Any suitable substance may be used for 50 retaining the moisture, but I have found that common blotting-paper will retain moisture as long or longer than any other substance, retaining it from five to six weeks, and is con-

venient to use, as well as cheap and easily attainable.

In the drawings I have shown one method 55 of applying my invention, consisting in a coil of blotting-paper, A, within a woven wire-cloth casing, B, the ends of the wire-cloth casing being provided with covers C' C², and suspended in the top of a show-case, D. 60

Beneath the wire cloth casing a sheet-metal trough, E, is arranged, to catch any surplus moisture or water that may drop from the blotting paper in the event of its being charged too fully with water, thus protecting the goods 65 or cigars from drippings.

The casing containing the blotting-paper will be immersed in water until the blotting-paper has taken up as much moisture as it will hold, and when the surplus water has 70 run off it will be suspended in the show-case, as shown. Or one of the covers C' or C² may be removed and the water poured upon the paper until it is fully charged.

Any suitable substance that will retain 75 moisture may be used instead of blotting-paper, it being desirable that some substance should be used that will retain the moisture for a long time, and that the casing should be pervious, to allow the moisture to escape, or, 80 rather, to allow the air to enter and become impregnated with the moisture.

Having described my invention and set forth its merits, what I claim is—

1. The combination, with the receptacle for 85 cigars, &c., of a device for impregnating the air in said show-case with moisture, consisting of a casing, B, covers C' C², trough E, and a moisture producing and retaining substance, A, substantially as described, and for the purpose set forth.

2. The moistening device for cigar receptacles, consisting of the wire cloth cylinder provided at each end with a metallic cap, the metallic trough connecting said caps and the 95 coil of bibulous material carried by said cylinder, substantially as set forth.

In testimony whereof I have hereunto set my hand in presence of two subscribing witnesses.

LEOPOLD JOSEPH ARTHUR LAURIER.
